UNITED STATES PATENT OFFICE.

BION D. FORD, OF CLEVELAND, OHIO.

MILLING-MACHINE CUTTER.

1,313,628.

Specification of Letters Patent. Patented Aug. 19, 1919.

Application filed November 27, 1916. Serial No. 133,526.

To all whom it may concern:

Be it known that I, BION D. FORD, a citizen of the United States, residing at Cleveland, in the county of Cuyahoga and State 5 of Ohio, have invented a certain new and useful Improvement in Milling-Machine Cutters, of which the following is a full, clear, and exact description, reference being had to the accompanying drawings.

10 This invention relates generally to milling machine cutters, and more particularly to one having detachable blades, the object of the invention being to provide a highly efficient milling machine cutter at a reasonable cost; and another object is to provide one in which the blades can be quickly and easily removed for replacing; and a still further object is to provide a milling machine cutter having detachable blades in 15 which the blades will be held securely against radial, lateral or wobbling movement after they have once been fastened in the body of the cutter.

With these objects in view, and certain others which will appear hereinafter, the invention consists in the novel construction of the blade and also in the novel manner of constructing the blade receiving socket in the body portion of the cutter, and in the 20 manner of securing said blade in the socket.

The invention consists also in certain details of construction and novelties of combination both which will more fully appear as the description proceeds, and will be 25 pointed out in the appended claims.

In the drawings forming a part of this specification—

Figure 1 is a detail perspective view illustrating a portion of a cutter, one of the cutter blades and fastening pins being removed;

Fig. 2 is a side elevation of a cutter constructed in accordance with my invention, three of the blades being removed from the 30 body portion thereof;

Fig. 3 is a sectional view of the body portion taken on the line 3—3 of Fig. 2;

Fig. 4 is a detail view of the locking pin, and;

50 Fig. 5 is a detail perspective view of the blade showing the cutting edge.

In the practical embodiment of my invention, I employ a substantially circular body portion A preferably of nickel steel or soft 55 steel; heat treated and case hardened; this

body being of suitable axial thickness and having the central portion thereof shaped for attachment to a shaft or arbor.

In the periphery of this body is cut a series of equidistant blade receiving sockets 60 B, each cut extending entirely through the body, in line with the axis thereof. One wall C of the socket is cut on a radial line as shown, while the opposite wall D is parallel with the wall C. The bottom of the 65 socket is concaved, being cut on an arc of a circle, the center of which is in a central axial plane of the body, the radius being in excess of the depth of the socket.

The blade F is made of high speed tool 70 steel and is of a thickness to fit snugly between the walls C and D and has the bottom G curved upon the arc of a circle corresponding with the curved bottom E of the socket, so that, when the blade is inserted 75 radially into the socket it will seat perfectly in the body and will occupy a perfectly true position axially therein.

In order to securely fasten each blade in its socket I employ a pin H having a flat face H', 80 and this flat face is cut upon a very slight taper, that is about 2°. Pin receiving holes I are bored through the body, these holes being of the same diameter as the pins H and they are so positioned as to intersect with 85 the wall C of each socket, the part of the wall intersected being substantially coextensive with the flat face H' of the pin, leaving wall portions upon the inner and the outer edges of the recess. These holes I are also 90 bored on an angle of 2°, and the socket may therefore be described as having flat walls and a curved bottom, one of its walls having a longitudinal recess slightly obliqued.

The blade F has one continuous flat face 95 K which contacts with the flat wall D of the socket, and the cutting edge face of the blade is flat for a portion of its length as shown at L, this flat portion being of such length that the inner portion contacts with 100 the wall C outside the recess I. The extreme inner portion of this face is also flat as shown at M and contacts with the wall of the socket inside of the recess, but between the flat portions L and M this face of the 105 blade is beveled or cut away as at N, the beveled or cut away portion extending from the part M and terminating in the shoulder O at the inner end of the portion L. This bevel M is substantially coextensive with the 110

flat face H' of the pin and is cut upon an angle of from 5° to 8°.

The flat face K of the blade is the same width as the body portion A but the cutting edge portion is slightly wider as shown clearly in Figs. 1 and 5.

Each blade is inserted radially in its particular socket until its convexed end seats firmly in the concaved bottom of the 10 socket, the beveled or cut-away portion of the cutting edge face being arranged opposite the recessed wall of the socket. The pin is then inserted in this recessed portion of the socket, and driven home, securely locking 15 the blade in the body and holding the same against radial axial and wobbling movement.

It will be understood that when the blade needs replacing it can be removed by simply 20 driving the pin out and lifting the blade from the socket. A milling machine cutter constructed as herein shown and described has been found to fully carry out and accomplish all of the objects hereinbefore referred to.

Having thus described my invention, what I claim is:—

1. A milling machine cutter comprising a body portion having peripheral blade sockets, the bottom of each socket being concaved, a blade having its bottom convexed to fit the concaved bottom of said socket and a wedge positioned in the socket parallel to the axis of the cutter and engage said 35 socket and blade and hold said blade in said cutter.

2. A milling machine cutter comprising a body portion having peripheral blade receiving sockets, the bottom of each socket 40 being concaved on the arc of a circle, one wall of said socket being recessed, said recess being parallel to the axis of the body of the cutter, blades fitting into said sockets, the bottom of each blade being convexed and 45 curved on the same arc as the concaved bottom of socket, and a wedge adapted to be inserted in the longitudinal recess of each socket, said wedge having a flat face adapted

to engage a corresponding face upon the blade.

3. A milling machine cutter comprising a body portion having peripheral blade receiving sockets, blades adapted to fit into said sockets, the bottom of each socket and the end of each blade being correspondingly 55 shaped, a recess in one wall of the socket, said recess being parallel to the axis of the body portion of cutter, the blade having a recess in the face thereof opposite the longitudinal recess of the socket, and a wedge 60 having a flat face adapted to engage the recessed face of the blade, said wedge being inserted in the longitudinal recess in the socket wall.

4. A milling machine cutter comprising a 65 body portion having peripheral blade receiving sockets, the bottom of each socket being centrally depressed, one wall of each socket being recessed, said recess being oblique, blades adapted to be inserted in said 70 sockets, each blade having its bottom shaped to correspond to the centrally depressed bottom of the socket and each blade having its face opposite the socket recess cut away upon a flat incline, and a pin having a tapered flat face adapted to engage the flat 75 inclined face of the blade, said pin being inserted in the socket recess.

5. A milling machine cutter comprising a body having peripheral sockets and blades 80 seated therein, each socket having a centrally depressed bottom and each blade a bottom corresponding in shape to the centrally depressed bottom of the socket, each socket having also a tapered recess in one 85 wall thereof parallel with the axis of the cutter and each blade having one face thereof cut away upon an incline, said cut away face being flat, and locking pins for locking 90 said blades in the sockets each pin being adapted to fit in the socket recess and also having a tapered flat face adapted to engage the flat inclined face of the blade.

In testimony whereof, I hereunto affix my signature.

BION D. FORD.
